UNITED STATES PATENT OFFICE

165,609

ELECTRIC LAMP WITH DOUBLE-FACED MIRROR FRAME

William Sablotny, Decatur, Ill.

Application September 4, 1951, Serial No. 16,498

Term of patent 14 years

(Cl. D48—20)

To all whom it may concern:

Be it known that I, William Sablotny, a citizen of the United States, residing at Decatur, State of Illinois, have invented a new, original, and ornamental Design for an Electric Lamp With Double Faced Mirror Frame, of which the following is a specification, reference being had to the accompanying drawings, forming a part hereof.

Figure 1 is a front elevational view of an electric lamp with double faced mirror frame, showing my new design;

Figure 2 is an end elevational view thereof; Fig. 3 is a top plan view, the shade being omitted for convenience of illustration; and

Fig. 4 is a fragmentary rear elevational view, the upper portion being broken away to conserve space.

I claim:

The ornamental design for an electric lamp with double faced mirror frame, as shown.

WILLIAM SABLOTNY.
